UNITED STATES PATENT OFFICE.

EDGAR C. WHITE, OF BELMAR, NEW JERSEY.

PLANT-BOX.

1,239,994.

Specification of Letters Patent. Patented Sept. 11, 1917.

Application filed July 3, 1916. Serial No. 107,382.

To all whom it may concern:

Be it known that I, EDGAR C. WHITE, a citizen of the United States, residing at Belmar, in the county of Monmouth and State 5 of New Jersey, have invented certain useful Improvements in Plant-Boxes, of which the following is a specification, reference being had therein to the accompanying drawing.

This invention relates to improvements in 10 plant boxes, one object of the invention being the provision of a box for forcing vegetable or flower plants and which may be used within or without the hothouse.

A further object of this invention is the 15 provision of a box of this type which is simple, durable and inexpensive in construction, and thoroughly efficient and practical in use.

In the accompanying drawings:

20 Figure 1 is a transverse section of this invention.

Fig. 2 is a similar section taken at right angles thereto.

25 Fig. 3 is a perspective view of the complete top removed, and

Fig. 4 is a fragmentary detail showing co-operating cleats on the front and side plates.

Referring to the drawings, the numeral 10 30 designates a single sheet of metal which provides the two side walls 11 and the rear wall 12 of the present box, the lower edges of such walls being provided with the in and upturned flanges 13, while the forward edges 35 of the side walls are provided with the out-turned flanges 14.

The bottom 15 of the box is provided with the three downturned flanges 16 which co-operate with the flanges of the rear and side 40 walls to maintain the bottom in position while the forward edge is provided with the upturned lip 17.

The front wall 18 of the box is provided with the inturned edges 19 having each a 45 cleat 20 which co-operates with the forward flanges of the side walls to slidily attach the front wall in position, while the lower edge of the front wall is adapted to fit upon the bottom within the forward lip thereof.

50 In assembling this much of the box, the

bottom is slipped in place from above so that its flanges will coöperate with the flanges of the rear and side walls, the front wall being inserted from above the upper edges of the side walls to slidily engage 55 the flanges thereof until its reinforced edge 21 is flush with the upper edges of the side and rear walls.

The cover carrying frame 22 of the present device is provided with the rim 23 which 60 is adapted to be inserted within the upper open end of the box so that its outwardly extending reinforcing edges 24 will rest upon the upper edges of the front, rear and side walls of the box, and at the same time 65 provide a clamping support for the screen top 25 of the cover.

Two opposite reinforced edges of the cover of the box are each provided with the U-shaped in cross section integral cleat 26 70 which slidably receives the sheet 27 of glass. Thus the glass may be removed at will to permit of the circulation of air within the box, and will when closing the same, produce an exceedingly practical cold frame for 75 forcing plants.

In use, the present device is filled to the proper depth with soil and the seed planted therein, the complete cover having been previously removed. The complete cover is 80 then placed in position and the seed is permitted to germinate.

When the plants have reached sufficient size to transplant and it is desirable to remove them for transplanting, the complete 85 cover is removed and the front wall of the box is also removed, thus permitting free access to the plants through the soil, so that a certain portion of the soil may be removed with each plant to insure a better transplanting operation without deleteriously affecting the plants.

What I claim as new is:

A plant box, including rear and side walls made from a single sheet of material and 95 each provided with a cleat upon its lower edge, the side walls being provided with cleats upon the front edges thereof, a removable bottom engaging the cleats upon the lower edge of the rear and side walls, a 100

front wall having cleats for slidably engaging the cleats upon the forward edge of the side walls, a removable cover consisting of an open frame having a rim for insertion within the rear, front and side walls of the box, limiting portions for engagement therewith, a screen attached to said limiting por-

tions, two of the opposite limiting portions being provided with flanges projecting therebeyond, and a removable sheet of transparent material mounted in said flanges. ¹⁰

In testimony whereof I affix my signature.

EDGAR C. WHITE.
